Primary Examiner — Cynthia Ramirez*Assistant Examiner* — Xavier Marti-Santos(74) *Attorney, Agent, or Firm* — Blank Rome LLP(57) **CLAIM**

We claim the ornamental design for an electric nail file system, as shown and described.

DESCRIPTION

FIG. 1 is a front perspective view of an electric nail file system showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is another front perspective view shown in an alternate configuration; and,

FIG. 9 is another front elevational view.

The broken lines in the figures are for the purpose of illustrating portions of the electric nail file system, which form no part of the claimed design. The electric nail file system is shown with a symbolic break in its length. The appearance of any portion of the article between the break lines forms no part of the claimed design. The circular stippling showing on a ring on the front side of the controller in FIG. 9 is for illustrating illumination of the ring in an illuminated state.
